C. G. BARRETT,
INTERNAL COMBUSTION ENGINE.
APPLICATION FILED JUNE 14, 1921.

1,415,858.

Patented May 16, 1922.

FIG. 1.

FIG. 2.

UNITED STATES PATENT OFFICE.

CHARLES G. BARRETT, OF BROOKLINE, MASSACHUSETTS, ASSIGNOR TO WORTHINGTON PUMP AND MACHINERY CORPORATION, OF NEW YORK, N. Y., A CORPORATION OF VIRGINIA.

INTERNAL-COMBUSTION ENGINE.

1,415,858.

Specification of Letters Patent. Patented May 16, 1922.

Application filed June 14, 1921. Serial No. 477,376.

To all whom it may concern:

Be it known that I, CHARLES G. BARRETT, a citizen of the United States, residing at Brookline, county of Norfolk, and State of Massachusetts, have invented certain new and useful Improvements in Internal-Combustion Engines, fully described and represented in the following specification and the accompanying drawings, forming a part of 10 the same.

The present invention has for its object the conservation of lubricant in internal combustion engines, especially multiple cylinder engines of the crosshead type, and 15 aims especially to provide simple and efficient means for accomplishing this result by applying scavenging or piston compressed air to prevent the oil being carried upward so as to be blown into the cylinder and 20 for returning the oil to the supply, and in carrying out the invention, I preferably provide chambered stuffing-boxes for the piston-rod and supply scavenging or piston-compressed air to said chambers during the up- 25 strokes of the pistons, thereby preventing lubricant working through the stuffing boxes from being blown during scavenging into the power cylinders and burned, with consequent waste of lubricant and increased smokiness 30 of the exhaust. Any lubricant that may work into the stuffing box chambers is returned by the air to the oil supply, or other receptacle, for re-use, thus securing the minimum of oil waste consistent with ef- 35 ficient lubrication of the piston-rods.

For a full understanding of the invention, a construction embodying the same in its preferred form, as applied to a two-cylinder engine, will now be described in detail in 40 connection with the accompanying drawings, and the novel features thereof then be pointed out in the claims.

In the drawings—

Figure 1 is a horizontal section of a two cylinder two-cycle engine, which may be of the Diesel type, with enclosed crosshead guide and crank casing;

Figure 2 is a transverse section on the line 2—2 of Fig. 1, and

Figure 3 is an enlarged central section of the piston-rod stuffing-boxes and cross-over connections.

Referring now to the drawings, and particularly to Fig. 1, the invention is shown 55 as applied to an internal combustion engine

with but two cylinders, A, B, although it will be understood that equally satisfactory results may be secured in engines having any number of cylinders. As clearly shown in Fig. 2, the engine in connection with which the invention is shown has inner crosshead guide and crank casings 10 and outer casings 11 which form scavenging air chambers 12, 12' for the respective engines, into which air for scavenging purposes is alternately drawn in on the upstrokes of the pistons *a*, *b* through automatic inlet valves 1 and compressed in each of said chambers on the downstrokes of the pistons, the piston rods 2, 2' passing through stuffing boxes 4, 4' mounted above the cross-head guides as usual.

In order to prevent lubricant adhering to the piston-rods from working up through the stuffing boxes, with consequent loss thereof by burning and increased smokiness of the exhaust as a result, the stuffing boxes 4, 4' are provided with chambers 5 (Fig. 3), preferably formed by the insertion of lantern glands 6 between the usual packing rings. These chambers 5, when so formed, are provided with inlet and outlet channels 7, 8, respectively, formed in the stuffing box walls in any suitable manner, and the inlets 7 have tapped thereto cross-over connections 9 leading from each stuffing box inlet 7 to the scavenging air chambers of opposite cylinders. The connections 9 are preferably provided with non-return valves of any well-known type, indicated generally at 13, 90 to prevent back-flow.

From the foregoing it will be obvious that, as the cranks C are set at an angle of 180° apart, the pistons *a*, *b* will of course reciprocate alternately. Assuming now that the 95 parts are in the positions shown in Fig. 1, that is, with the piston *a* about to begin the down-stroke, air compressed in the chamber 12 by the downstroke of the piston will be forced through the connection 9, past non-return valve 13, to chamber 5 of stuffing box 4', and such pressure will be maintained in such stuffing box chamber until the piston-rod 2' passing through stuffing box 4' begins its down-stroke. The maintenance of this 105 air pressure in the piston-rod stuffing-box chambers 5 effectually prevents passage of lubricant beyond such chambers, and any lubricant collecting in the chambers 5 will be forced through the outlets 8 and such oil 110

2
returned to the crank casings, in the construction shown, or elsewhere if desired.

It will be understood that various changes may be made in the construction and still be within the scope of the claims, and that while the invention is especially applicable to multiple cylinder internal combustion engines of the two-cycle type illustrated, it may be applied with equal advantage to other engines in which pressure is similarly available for oil recovery.

What is claimed is:

1. Means for conserving lubricant in engines, comprising a chamber open to the piston rod for receiving oil therefrom, and means for supplying a piston-compressed medium to said chamber and delivering oil therefrom.

2. Means for conserving lubricant in engines, comprising a piston-rod stuffing box having a chamber therein, and means for supplying a piston-compressed medium to said chamber on the movement of the piston-rod and delivering oil therefrom.

25 3. Means for conserving lubricant in internal combustion engines, comprising a piston-rod stuffing box, a chamber for receiving oil carried by the piston-rod through the stuffing box, and a connection for supplying scavenging air to said chamber for delivering the oil.

30 4. Means for conserving lubricant in mul-

tiple cylinder internal combustion engines, comprising chambers receiving oil from lubricated parts of said engines, outlets, 35 therefor, and cross-over connections between the respective oil chambers and scavenging air chambers of other cylinders for supplying air under pressure to said oil-receiving chambers.

40 5. Means for conserving lubricant in multiple cylinder internal combustion engines, comprising stuffing boxes for the respective piston-rods having chambers therein, outlets therefor, and cross-over connections between 45 the respective oil chambers and scavenging air chambers of other cylinders for supplying air under pressure to said oil-receiving chambers.

6. Means for conserving lubricant in multiple cylinder internal combustion engines, comprising a plurality of piston-rod stuffing boxes having chambers therein, outlets for said chambers, outwardly opening check valves in said outlets, cross-over connections between 55 the scavenging air chambers of other cylinders and said stuffing box chambers for supplying piston-compressed air thereto at predetermined intervals, and non-return valves in said cross-over connections.

60 In testimony whereof, I have hereunto set my hand.

CHARLES G. BARRETT.
